NECTICUT

INTERNAL COMBUSTION ENGINE

Original application filed June 5, 1928, Serial No. 283,081. Divided and this application filed August 31,
1929. Serial No. 389,781.

This invention relates in general to internal combustion engines and is more particularly concerned with thermostatic controls governing the operation of the same between certain ranges of combustion cylinder temperatures. This invention is a division from our original application, Serial Number 283,081, filed June 5, 1928, and is especially directed to such thermostatic devices as applicable to spark adjustment control.

Internal combustion engines have a tendency to overheat under conditions of excess load, incorrect carburetion due to the use of low grade fuels or improper adjustment of fuel proportions, incorrect spark timing and other adverse conditions. Such conditions frequently cause detonation, which in turn causes further overheating, poor lubrication, loss in horse-power output and the final seizing of the pistons within their cylinders and the destruction of the engine.

It is well recognized that failure of an engine due to overheating is due to excessive temperature of the cylinder head or cylinder walls, and the excessive temperature may be caused either by high combustion temperature, deficiency of the cooling system, or a condition such as detonation, which causes a disproportionate part of the heat of combustion to be transferred to the cylinder walls.

The prior art contains efforts to regulate engine temperatures by control of the cooling means, as, for example, thermostatic control of the cooling water circulation. Such means are effective to maintain a certain minimum temperature which may be desirable for operation, but are powerless to limit the maximum temperature of the combustion chamber or cylinder whenever the conditions of operation cause the evolution and transfer to the cylinder walls of more heat than the cooling system is capable of absorbing.

In order to remove the danger which might

otherwise arise from excess loads, poor fuel selection, improper spark timing, deficiency of the cooling system or other causes of overheating, it is the purpose of this invention to provide a means, governed by cylinder 50 temperature, for controlling the amount of heat supplied to the cylinder walls. In general any control is effective which operates to reduce the pressure and/or temperature of combustion; or to prevent detonation if 55 conditions likely to cause detonation are present.

Combustion temperature may be lowered and detonation, if any, reduced by closing the throttle, retarding the spark, enriching 60 the fuel mixture, or by various combinations of the three. It is, therefore, an object of this invention to provide a means, governed by combustion cylinder temperature for controlling, within certain bounds, the setting 65 of the spark adjustment control.

It is the prime object of this invention to position a thermostat at a point vitally affected by overheating, such as on, or adjacent to, the barrel or head of one of the engine 70 cylinders, and to connect the same by suitable means to the spark adjustment control in such a manner that excessive cylinder temperatures will result in a retarding of the spark control to the effect that destructive 75 temperatures will be avoided.

It is another object of this invention to provide in the connections between the thermostatic device and the engine spark adjustment control a certain degree of lost motion to prevent the thermostatic device from becoming effective until a predetermined cylinder temperature has been attained, and to provide for adjustment in these connections.

It is a further object of our invention to provide an adjustable linkage between two magnetos or distributor heads on the same engine whereby both may be influenced by a single thermostat.

Other objects of our invention will appear

in the following specification and claims and will be disclosed in the accompanying drawing in which—

The figure is a rear elevation of a portion 5 of a V-type internal combustion engine with our thermostatic control mounted thereon and illustrated partly in section.

Referring now with greater particularity 10 to the drawing, it will be seen that our device is comprised as follows:

A thermostat 1, preferably though not necessarily, comprised of two dissimilar metals having different co-efficient of expansion and welded or riveted together, is secured by any suitable means, such as is illustrated at 2, to the cylinder block 3 of the engine at a point at, or adjacent to, the head of the said cylinder. At its free end the thermostat has, fixedly or integrally secured thereto, a pin 20. This pin is adapted to travel in a slot 21 in the upper portion 22 of a spark adjusting control rod 23. This rod is comprised of two principal parts 23 and 24 adjustably securable to each other by a gland 25 having oppositely screw-threaded bores 26 and 27. A lock nut 28 is provided to hold the rod parts in any position to which they may have been adjusted.

The lower rod portion 24 is pivotally connected at its lower end to the spark lever 26' which in turn is pivotally connected to its companion spark lever 27' by means of a rod 28', the engine shown being of the dual ignition type. The rod 28' is, in turn, pivotally connected to the hand spark control rod 29. It will be noted that the rod 28' is divided into two portions adjustably connected to each other by a gland 29'. The purpose of this adjustable connection is to permit of adjustment of the relative settings of the two spark controls to the cylinders in the dual ignition system. The effective length of the composite rod 23—24 may be adjusted by means of the gland 25 and so vary the setting at which the pin 20 will reach the bottom of the slot 21 and hence the temperature setting beyond which the thermostat will cause a retarding of the spark. The movement of the parts is shown in dotted lines as illustrating 65 the action of the thermostatic control under conditions of excess temperatures.

From the foregoing it will be seen that the operation of our device is as follows:

When the engine temperature rises the thermostat moves in the direction of the position shown in dotted lines. After the pin 20 reaches the bottom of the slot 21, any further depression of the free end of the thermostat caused by increased or excessive temperatures 60 will result in moving the spark lever 24 to retard the spark. This in turn will result in a lowering of the combustion chamber pressure and temperature. The gland 25 provides for adjustment of the position of the rod 23 and its eyelet 21 relative to the pin 20 and

hence regulates the point at which the thermostat will become effective. The gland 29 provides for a differential spark setting between the two sparking devices.

Having thus described our invention what 70 we claim is—

1. In combination, with an internal combustion engine having a spark adjusting control, a thermostat mounted in thermal communication with said engine, and means 75 operatively connecting said thermostat and said spark control to actuate the latter, said means being ineffective to operate said control at any normal engine temperature but operating to retard the same when the engine 80 temperature rises to a predetermined excessive degree.

2. In combination, with an internal combustion engine having a spark adjusting control, a thermostat mounted on said engine, 85 and means operatively connecting said thermostat and said spark control to actuate the latter, said means being ineffective to operate said control at any normal engine temperature but operating to retard the same 90 when the engine temperature rises to a predetermined excessive degree.

3. In combination, with an internal combustion engine having a spark adjusting control, a thermostat mounted on said engine, 95 and means operatively connecting said thermostat and said spark control to actuate the latter when the temperature of said engine reaches a predetermined degree, and means 100 for adjusting said connecting means to vary the point at which said thermostat becomes effective upon said spark control.

4. In combination, with an internal combustion engine having a spark adjusting control, a thermostat mounted on said engine, 105 and means operatively connecting said thermostat and said spark control to retard the latter when the temperature of said engine reaches a predetermined degree, and means 110 for adjusting said connecting means to vary the point at which said thermostat becomes effective upon said spark control.

5. In combination, with an internal combustion engine having a spark adjusting control, a thermostat mounted on said engine 115 and in thermal communication therewith, a rod operatively connecting said thermostat and said spark control to actuate the latter, said rod being provided with means whereby said thermostat is ineffective to operate said control at any normal engine temperature but operates to retard the same when the engine 120 temperature rises to a predetermined excessive degree.

6. In combination, with an internal combustion engine having a spark adjusting control, a thermostat mounted on said engine and in thermal communication therewith, a rod operatively connecting said thermostat and said spark control to actuate the latter 125 130

when the temperature reaches a predetermined degree, and means for adjusting the effective length of said rod.

7. In combination, with an internal combustion engine having a spark adjusting control, a thermostat mounted on said engine and in thermal communication therewith, a rod operatively connecting said thermostat and said spark control to actuate the latter when the temperature reaches a predetermined degree, said rod having means permitting of lost motion between said thermostat and said control to the extent that said thermostat will be ineffective to operate said control at any normal engine temperature.

8. In combination, with an internal combustion engine having a spark adjusting control, a thermostat mounted on said engine and in thermal communication therewith, a rod operatively connecting said thermostat and said spark control to actuate the latter when the temperature reaches a predetermined degree, and means for adjusting the effective length of said rod, said rod having means permitting of lost motion between said thermostat and said control to the extent that said thermostat will be ineffective to operate said control at any normal engine temperature.

30 9. In combination, with an internal combustion engine having a spark adjusting control, a thermostat mounted on said engine and in thermal communication therewith, a rod operatively connecting said thermostat and said spark control to actuate the latter when the temperature reaches a predetermined degree, a pin on said thermostat, said rod having an elongated eyelet adapted to act as a guide for said pin.

40 10. In combination, with an internal combustion engine having a dual ignition system, two spark distributing control devices, and means operatively connecting said distributing devices, said means being adjustable to provide a differential spark timing between said devices, a thermostat in thermal communication with said engine, and means operatively connecting said thermostat to said control devices to actuate the latter in response to engine temperature changes, said last named means being adapted to permit of normal engine temperature increases without influencing said controls but operating to retard the same when a point of excess temperature is reached.

50 11. In combination, with an internal combustine engine having a dual ignition system, two spark distributing control devices, and means operatively connecting said distributing devices, said means being adjustable to provide a differential spark timing between said devices, a thermostat in thermal communicatiton with said engine, and means operatively connecting said thermostat to said control devices to actuate the latter in

response to engine temperature changes, said last named means being adapted to permit of normal engine temperature increases without influencing said controls but operating to retard the same when a point of excess 70 temperature is reached, and means for adjusting said last named means to determine the temperature at which said thermostat will become effective upon said controls.

In testimony whereof we have affixed our 75 signatures.
